Specification for Design.

Patented Aug. 18, 1914.

Application filed June 5, 1908. Serial No. 437,023. Term of patent 14 years.

To all whom it may concern:

Be it known that I, OTIS A. MYGATT, a citizen of the United States, residing at New York, in the county of New York and State of New York, have invented a new, original, and ornamental Design for Shades, Reflectors, or Similar Articles, of which the following is a specification, reference being had to the accompanying drawings, forming part thereof.

Figure 1 is a top plan view of a shade or reflector embodying my invention; Fig. 2 is a bottom plan view of the same; and Fig. 3 is an elevation.

The design constituting my invention is applied to glass shades or reflectors having a contour substantially as shown, and having upon the outer surface thereof radially disposed prisms arranged substantially as shown.

I claim—

The ornamental design for a shade, reflector or similar article, substantially as shown and described.

OTIS A. MYGATT.
